Attorney.

UNITED STATES PATENT OFFICE.

HENRI FRANÇOIS CABIRAU, OF PARIS, FRANCE.

CARBON FOR ELECTRIC LAMPS.

SPECIFICATION forming part of Letters Patent No. 542,625, dated July 16, 1895.

Application filed April 11, 1895. Serial No. 545,296. (No model.) Patented in France September 18, 1894, No. 241,477.

To all whom it may concern:

Be it known that I, HENRI FRANÇOIS CABIRAU, a citizen of France, residing at Paris, France, have invented certain new and useful

5 Improvements in Carbons for Electric Lamps, (for which I have obtained French Letters Patent No. 241,477, dated September 18, 1894;) and I do hereby declare the following to be a full, clear, and exact description of the invention, 10 such as will enable others skilled in the art to which it appertains to make and use the same, reference being had to the accompanying drawings, and to letters of reference marked thereon, which form a part of this 15 specification.

My invention has relation to a carbon pencil or stick for electric-arc lamps of the class composed of two tubular sections, one section being substantially cylindrical and inclosed by 20 the other section, which is substantially tubular and separated therefrom by chambers or channels for the passage of air, and it relates particularly to the construction and arrangement of such a carbon pencil or stick.

25 The principal objects of my invention are, first, to provide a carbon stick or pencil for an electric-arc lamp of simple construction and adapted to be consumed much more slowly than the carbon pencils now in use, and, second, 30 to provide in electric-arc lamps a carbon stick or pencil consisting of two sections of tubular form, one section being substantially cylindrical and inclosed by the other section, which is substantially tubular, in such a manner 35 that there is an air channel or passage formed between the two sections.

My invention consists of a carbon pencil for electric-arc lamps, constructed and arranged in substantially the manner hereinafter described and claimed.

The nature, characteristic features, and scope of my invention will be more fully understood from the following description, taken in connection with the accompanying drawings, forming a part hereof, in which—

45 Figure 1 is a view, partly in vertical section and partly in elevation, of a carbon pencil embodying the main features of my invention, illustrating a positive carbon pencil of substantially cylindrical form united to an outer tubular section by means of cement, the outer

section being provided with internal ribs supporting the interior pencil and separating the same from the internal walls of the tubular section. Fig. 2 is a horizontal section on the line $x-x$ of Fig. 1. Fig. 3 is a similar section taken through a negative carbon pencil, and showing the inner tubular carbon pencil provided with ribs for separating the inner pencil from the outer tubular inclosing-section. Fig. 4 is a vertical section on the line $Z-Z$ of Fig. 5, illustrating a modified form of pencil in which the inner tubular core or pencil is integral with the outer tube and the pencil and tube separated by channels or air-passages 65 extending the entire length of the compound pencil. Fig. 5 is a horizontal section on the line $y-y$ of Fig. 4; and Fig. 6 is a horizontal section of a pencil, showing a modification of the pencil illustrated in Figs. 4 and 5.

Referring to the drawings, Figs. 1, 2, and 3 illustrate a compound pencil, in which the sections are first formed separately and then placed together in operative position and united by means of cement or the like. Referring to the said figures, A represents a cylindrical tubular pencil of carbon or its equivalent, and B represents an outer tubular pencil of preferably carbon inclosing the inner pencil A, nested together. In the construction of 80 the positive carbon it has been found advantageous to form on the outer tube B a series of ribs b, which project from the interior of the tube B, while in the negative carbon the pencil A' is preferably a cylinder and is provided with the external ribs a, as shown in Fig. 3. These ribs a or b serve to separate the interior pencil A' or A from the encircling tube B' or B, so that air spaces are formed between the two sections A' and B' or A and 85 B. The two sections A and B may be united at one or both ends by means of cement c placed in a portion of the space separating the two sections, substantially as indicated in Fig. 1 of the drawings.

90 A modification of the foregoing arrangement is shown in Figs. 4, 5, and 6, in which the pencil consists of one section D, channeled or grooved internally the entire length of the pencil, as indicated at d. There is thus 100 formed a single pencil D, partially hollowed, the spaces or grooves d corresponding to the

spaces formed between the separable sections A and B or A' and B' of the compound pencil, as hereinbefore explained. In Fig. 6 the interior channels d' are of different shape in cross-section from the channels d of Figs. 4 and 5, but in other respects the construction is the same. The spaces thus formed in the carbons of either form shown permit the circulation of air so that the carbon, when consumed, will burn more slowly, without impairing the brilliancy of the light.

Having thus described the nature and objects of my invention, what I claim as new, and desire to secure by Letters Patent, is—

15 1. A carbon for electric arc lamps, consisting of two pencils nested together, the inner pencil being provided with a central opening and radial channels or air passages formed

between the nested pencils, substantially as and for the purposes set forth. 20

2. A compound carbon pencil for electric arc lamps, consisting of a carbon cylinder and a tube of carbon surrounding said carbon cylinder and separated by ribs therefrom, substantially as and for the purposes set forth. 25

3. A compound carbon pencil for electric arc lamps, consisting of two nested together pencils cemented to each other and air openings between the nested pencils, substantially as and for the purposes set forth. 30

In testimony whereof I affix my signature in presence of two witnesses.

HENRI FRANÇOIS CABIRAU.
